CLAIM

The ornamental design for a bag, as shown and described.

DESCRIPTION

FIG. 1 is a perspective view of a bag showing the new design;

FIG. 2 is a second perspective view thereof;

FIG. 3 is a third perspective view thereof;

FIG. 4 is a fourth perspective view thereof;

FIG. 5 is a front elevation view thereof;

FIG. 6 is a back elevation view thereof;

FIG. 7 is a right-side elevation view thereof;

FIG. 8 is a left-side elevation view thereof;

FIG. 9 is a top plan view thereof;

FIG. 10 is a bottom plan view thereof;

FIG. 11 is a fifth perspective view thereof;

FIG. 12 is a sixth perspective view thereof;

FIG. 13 is a seventh perspective view thereof;

FIG. 14 is an eighth perspective view thereof; and,

FIG. 15 is a ninth perspective view thereof.

The broken lines on the bag illustrate stitching that forms no part of the claimed design.

The broken lines in FIG. 15 depicting pens form no part of the claimed design.

1 Claim, 15 Drawing Sheets
